DICTATING MACHINE

Frank A. Ilenin, Bloomfield Hills, Mich., assignor to
Minnesota Mining and Manufacturing Company, St.
Paul, Minn., a corporation of Delaware

Filed Dec. 24, 1959, Ser. No. 58,810

Term of patent 14 years

(Cl. D26—14)

FIG. 1

FIG. 2

FIG. 3

FIG. 4

FIG. 5

FIG. 1 is a perspective view of a dictating machine, showing my new design;

FIG. 2 is a right side elevational view;

FIG. 3 is a left side elevational view;

FIG. 4 is a rear elevational view; and

FIG. 5 is a cross-sectional view thereof.

I claim:

The ornamental design for a dictating machine, substantially as shown and described.
